UNITED STATES PATENT OFFICE.

JOSEPH E. PLUMSTEAD, OF WILMINGTON, DELAWARE, ASSIGNOR TO THE JESSUP & MOORE PAPER CO., OF PHILADELPHIA, PENNSYLVANIA, A CORPORATION OF MASSACHUSETTS.

COOKING LIQUOR.

No Drawing. Original application filed April 18, 1923, Serial No. 632,927. Divided and this application filed January 18, 1924. Serial No. 687,133.

To all whom it may concern:

Be it known that I, JOSEPH E. PLUMSTEAD, a citizen of the United States, and resident of Wilmington, in the county of New Castle and State of Delaware, have invented certain new and useful Improvements in Cooking Liquors, of which the following is a specification.

This invention relates to an alkaline cooking liquor for the production of chemical pulp as used in paper making.

The principal object is the provision of such a liquor which will contain sulphur in such a form that the lignous or other acids of the wood will not cause the formation of compounds containing sulphur which will readily be decomposed. This difficulty has long been a problem, as it is known that the presence of sulphur has a desirable reaction upon the pulp, but the difficulty has been in placing the sulphur in the liquor in such form that it was not lost at one or more points in the cycle.

I have described in my co-pending application No. 632,927, filed April 18, 1923, of which this is a division, one method of introducing sulphur into the cycle as operated under the so-called soda process, which sulphur finds its way into the cooking liquor in such a form that the minimum amount of this element is lost in the cooking and other steps. I have found, however, upon chemical analysis of the liquor produced by carrying out the method described in my above mentioned application, that sodium thiosulphate, and sometimes sodium sulphite, are present, together with the usual sodium hydroxides

produced in the causticizing step where lime is added to the black ash leachings which contain sodium carbonate. I attribute 40 the beneficial results obtained to the presence of these compounds. It will thus be apparent that a liquor may be prepared and these compounds as such, added thereto before the cooking or digestion takes place. 45

The exact amount of the sulphur salts mentioned to be added will have to be determined by the one skilled in the art who is to employ the same, for the reason that the proportions vary between wide limits and 50 are dependent on the type of raw material used, the water content, the pressure and concentration obtained in the digestion, and other well known conditions. However, it is noted that only small amounts of sulphur 55 need be added upon completion of any cycle, which deficiency may be determined accurately at any one of various points in the cycle, by analysis.

It may be found desirable to utilize salts 60 of other metals of the alkali group in the cooking liquor, although the particular method mentioned forms salts which are desirable because of cheapness.

Having thus described my invention, what 65 I claim is:—

1. In the preparation of chemical pulp, the use of a cooking liquor comprising sodium hydroxide and sodium thiosulphate.
2. In the preparation of chemical pulp, 70 the use of a cooking liquor comprising a hydroxide and a thiosulphate.

In testimony whereof I affix my signature.
JOSEPH E. PLUMSTEAD.
